(57) **CLAIM**

The ornamental design for a metal framing layout square, as shown and described.

DESCRIPTION

FIG. 1 is a front top perspective view of the present invention. FIG. 2 is a top plan view of FIG. 1.

FIG. 3 is a bottom plan view of FIG. 1.

FIG. 4 is a left side elevation view of FIG. 1.

FIG. 5 is a right side elevation view of FIG. 1.

FIG. 6 is a front side elevation view of FIG. 1.

FIG. 7 is a back side elevation view of FIG. 1.

FIG. 8 is a front perspective view of another embodiment of the present invention.

FIG. 9 is a top plan view of FIG. 8.

FIG. 10 is a bottom plan view of FIG. 8.

FIG. 11 left side elevation view of FIG. 8.

FIG. 12 is a right side elevation view of FIG. 8.

FIG. 13 is a front elevation view of FIG. 8; and,

FIG. 14 is rear elevation view of FIG. 8.

The surfaces are lightly lined for contour only.

1 Claim, 10 Drawing Sheets
